UNITED STATES PATENT OFFICE.

WILLIAM L. KELLY, OF SPOKANE, WASHINGTON.

SEAL.

1,179,190.

Specification of Letters Patent.

Patented Apr. 11, 1916.

Application filed December 1, 1915. Serial No. 64,466.

To all whom it may concern:

Be it known that I, WILLIAM L. KELLY, a citizen of the United States, and a resident of Spokane, in the county of Spokane 5 and State of Washington, have invented an Improvement in Seals.

This invention is an improvement in seals and has particular reference to a car or package seal.

10 It is proposed to provide a device of this character which is preferably made from a single sheet of metal formed into a housing and locking device which, after being locked, cannot be opened without tearing or mutilating the same.

15 The device further embodies a structure of extreme simplicity which fact minimizes the cost of manufacture, and enhances the commercial value of the article.

20 The inventive idea involved is capable of receiving a variety of mechanical expressions, some of which, for the purpose of illustrating the invention, are shown in the accompanying drawing, in which—

25 Figure 1 is a perspective view of one of the seals constructed in accordance with the invention and shown in open position. Fig. 2 is a longitudinal sectional view of the same in closed or locking position. Fig. 3 is a transverse section on the line 3—3 of Fig. 2. Fig. 4 is a fragmentary perspective view of a somewhat similar construction to that shown in Fig. 1.

30 The drawing illustrates what are now thought to be preferred embodiments of the device in which the same comprises a single strip of any suitable metal such as iron or steel shaped to provide a housing generally indicated by the numeral 5. This housing is formed at one end of the strip and consists of an outer portion 6 composed of sides 7 and ends 8. The housing further consists of an inner portion 9 having the sides 10 and inner end 11, said inner portion being 35 adapted to be folded on the line 12 so that the sides 10 thereof will be received between the sides 7 of the outer portion, as best shown in Fig. 3. The sides 7 are of sufficient depth to permit the longitudinal edges 40 thereof to be bent over the longitudinal edges of the inner portion 9 as indicated at 45 13 in Fig. 3 whereby the parts will be retained in locking position. At the end 8 of the outer portion 6 opposite to that end 50 upon which the portion 9 is formed the material is thickened as best shown in Fig. 2

so as to admit of said end being bent without decreasing the efficiency of the device and said end is made of a considerably greater depth than the other end of the portion 6. A continuation of the thickened end 8 provides an elongated strap 14 which is also thickened as indicated at 15 and reduced in said thickened portion to provide shoulders 16. The reduced end of the strap 65 14 is provided with a lug 17 which, in Fig. 1, is normally flush with the flat surface of the strap, the material of which this structure is made being non-resilient, such as soft iron. In Fig. 4, the material of which the device 70 is formed is of a resilient nature such as steel so that when the lug 17 is formed therein the same may be originally bent into the position illustrated.

75 In practice, when it is desired to employ this seal to lock a package, car or the like, the strap 14 is bent, as shown in Fig. 2, and the extremity thereof is inserted through an elongated slot 18 formed in the thickened end 8 of the portion 6 until the shoulders 16 80 contact with said thickened end, and also through a similar slot 19 in the end 11 of the portion 9, said latter slot registering with the slot 18 when the parts are in the position shown in Fig. 2. The end of the 85 strap 14 is then further inserted into the housing until the locking lug 17 is entirely within said housing. When the structure shown in Fig. 1 is employed a suitable tool, shown in dotted lines in Fig. 2, may be inserted through an opening 20 formed in the portion 9 and said lug forced downwardly to the position shown in Fig. 2 whereupon the same will engage the inner face of the end 11 of the portion 9 and prevent the extremity of the strap from being withdrawn 90 from the housing. The extreme end of the strap 14 projects through a slot 21 in the outer end 8, said slot being in alinement with the slots 18 and 19. When a resilient material is used, the locking lug or tongue 17 will automatically assume the position shown in Fig. 2 thus obviating the necessity of employing a tool or other means to adjust the same to its locking position. 100 105

What is claimed is:

1. A seal composed of a single strip of metal bent at one end to provide a housing consisting of outer and inner portions, the former including sides and ends, the latter 110 having alined slots therein and joined to one of the ends of said outer portion and includ-

ing a top, sides and one end which is provided with a slot arranged contiguous to and registering with a slot in one end of said outer portion, the sides of said inner portion 5 being of less width than the sides of the outer portion whereby the longitudinal edges of the latter may be bent over the top of said inner portion for retaining the said portions in closed position, and a strip projecting from one of the ends of the outer portion of the housing and extending through said contiguous and registering openings in one end of the housing and also through the opening in the other end there- 10 of, said strip being provided adjacent its extremity with a locking tongue for engaging the interior of the end of said inner portion adjacent said contiguously arranged open- 15 ings.

20 2. A seal formed from a single sheet of metal bent to provide a housing consisting

of outer and inner portions, the ends of said portions being provided with alined slots, and a strap formed upon one end of the outer portion and reduced in width adjacent 25 its end to provide shoulders adapted to contact the adjacent end of the housing, the reduced end of the strap having a locking tongue formed therein and adapted for engagement with the interior of the end of the 30 inner portion of the housing when the parts are in locking position, the end upon which said strap is formed and a portion of the latter adjacent said end being thickened, and the portion of said strap adjacent said 35 shoulders and tongue being likewise thickened.

WILLIAM L. KELLY.
